UNITED STATES PATENT OFFICE.

WILLIAM R. E. NOHSE, OF NEW YORK, N. Y.

LUBRICATING APPARATUS.

Application filed October 23, 1926. Serial No. 143,650.

This invention relates to lubricating apparatus, an object of the invention being to provide an improved lubricating apparatus functioning as a grease cup, which may be entirely manual in its operation or semi-automatic, and which has many advantages, some of which may be enumerated as follows:

The device is simple in construction, easily assembled and most efficient in the performance of its functions;

All parts when once assembled remain in their proper relationship so that there is no danger of lost parts;

The device is positive in action, assuring thorough lubrication, and is economical in the use of lubricant;

It can be easily replenished and is dirt and dust proof;

The device may be easily manipulated and is also a safeguard against hot bearing surfaces;

The device is neat and attractive in appearance and strong and durable in use.

With these and other objects in view, the invention consists in certain novel features of construction and combinations and arrangements of parts which will be more fully hereinafter described and pointed out in the claims.

In the accompanying drawings—

Figure 1 is a top plan view, partly broken away and in section, illustrating my improved lubricating device;

Figure 2 is a view in vertical or longitudinal section;

Figure 3 is a view in transverse section, the section being taken at a point between the bonnet and the cap of the device;

Figure 4 is a perspective view of the retaining ring;

Figure 5 is a view in longitudinal section, illustrating a modification;

Figure 6 is a fragmentary view in section, illustrating another modification.

1 represents a cup or receptacle of any desired size adapted to receive lubricant and having a threaded nipple 2 at its lower end for attachment to the parts supporting the same. This nipple 2 is hollow and constitutes an outlet for the lubricant, and the upper end of the cup 1 is externally screw

threaded, as shown at 3, for the reception of an internally screw threaded cap 4 constituting a removable closure for the upper end of the cup.

The upper face of the cap 4 is depressed or recessed, as shown at 5, so as to accommodate and seat the base or disk 6 of my improved bonnet 7. This bonnet 7 is of general cylindrical form, the lower portion, at least, of which is internally screw threaded, as shown at 8, to mesh with an externally screw threaded plunger rod 9, the latter carrying a plunger 10 located in and fitting the cup 1. This plunger 10 may be provided with any ordinary means to render a snug fit in the cup so as to prevent discharge of the lubricant around the plunger.

The upper face of the cap 4 is somewhat enlarged at the center; or, in other words, upwardly offset and of circular form, constituting a circular enlargement or bearing 11 which fits in a correspondingly shaped recess 12 in the bottom of disk 6. This enlarged central portion 11 has an opening 13 therein, which is of circular form but less than a circle, having a flat or straight wall 14, and the plunger rod 9 is flattened on one side, as clearly shown, so as to move freely within the opening 13 but held by the flat wall 14 against turning movement.

The base or disk 6 of the bonnet 7 and the wall of the cap 4 are formed with registering grooves 15 and 16, in which a split retaining ring 17 is sprung so as to hold the parts in coupled engagement but permit a free turning movement of the bonnet. The bonnet is preferably formed with longitudinal slots 18 through which the plunger rod 9 may be observed so as to disclose just how much lubricant there is in the apparatus, and radial webs 19 are provided on the bonnet to facilitate a gripping thereof and to facilitate the turning movement of the bonnet.

The operation is as follows:

When it is desired to fill the cup or receptacle 1, the cap 4 is unscrewed and carries with it the bonnet and the plunger. Lubricant is then placed in the cup and the cap returned to its closed position. When a turning movement in one direction is imparted to the bonnet the screw threaded en-

gagement of the same and the plunger 9 will cause the plunger to move downwardly and extrude the lubricant.

In the modification illustrated in Figure 5 I disclose a form of plunger which is semi-automatic in its operation and which may be substituted for the plunger illustrated in Figure 2. In this form of my invention the plunger rod 9 of the form above described is made with a longitudinal bore 21 extending upwardly from its lower end the desired distance and accommodating an enlargement 22 on a rod 23. The lower end of the bore 21 is preferably restricted after the enlargement 22 is in the bore, as indicated at 24, to prevent the accidental removal of the rod.

The lower end of the plunger rod 20 has a disk 25 thereon, and a plunger 26 is secured to the lower end of rod 23. A helically coiled spring 27 is located around the rod 23 and interposed between the disk 25 and the plunger 26, the latter being recessed in its upper face to seat and house the spring 25 when the latter is fully compressed, as indicated by dotted lines in Figure 5. With this form of plunger and its cooperating parts the spring 27 will of course function to extrude lubricant automatically as it may be needed, and it is only necessary to move the plunger rod from time to time in order to put the spring under pressure.

In Figure 6 I illustrate a modified means for coupling the base or disk 6 of the bonnet 7 to the cap 4 of the lubricant cup 1. In this form of the invention the wall of the recess accommodating the disk 6 is screw-threaded, as shown at 27', to receive a removable ring 28 which overlaps an edge of the disk, and this ring may have wrench receiving recesses 29 therein.

It is of course to be understood that many other modifications may be made in the specific construction and detail parts and hence I do not limit myself to the exact construction but consider myself at liberty to make such changes and alterations as fairly come within the spirit and scope of the appended claims.

I claim:

1. A lubricating apparatus, including a receptacle, a removable cap on the receptacle, a screw threaded plunger rod mounted to move through the cap and held by the cap against rotary movement, a plunger con-

nected to the rod within the cup, and an internally screw threaded bonnet engaging the plunger rod and coupled to turn on the cap.

2. A lubricating apparatus, including a receptacle, a removable cap on the receptacle, a screw threaded plunger rod mounted to move through the cap and held by the cap against rotary movement, a plunger connected to the rod within the cup, an internally screw threaded bonnet engaging the rod, and a disk on the bonnet having coupled engagement with the cap and adapted to turn thereon.

3. A lubricating apparatus, including a receptacle, a removable cap on the receptacle, a screw threaded plunger rod mounted to move through the cap and held by the cap against rotary movement, a plunger connected to the rod within the cup, said cap having a depression or recess in its upper or outer face, a bonnet having internal screw threads engaging the threads of the plunger, a disk on the bonnet fitting the recess of the cap, and means coupling the disk and the cap but permitting turning movement of the disk in the recess of the cap, said means comprising a split ring fitting the opposing grooves in the disk and cap.

4. A lubricating apparatus, including a receptacle, a removable cap on the receptacle, a screw threaded plunger rod mounted to move through the cap and held by the cap against rotary movement, a plunger connected to the rod within the cup, an internally screw threaded bonnet engaging the plunger rod and coupled to turn on the cap, said bonnet having an opening therein through which the plunger rod is observable, and means on the bonnet for facilitating turning the same.

5. A lubricating device of the character described, including a receptacle, a cap on the receptacle, a screw threaded rod having a flat face located in an opening of the corresponding shape in the cap and held against turning movement, a bonnet coupled to the cap and having internal screw threads engaging the threads of the plunger rod, said plunger rod having a longitudinal bore, a plunger, a rod connected to the plunger and movable in said bore, and a spring interposed between the plunger and the first mentioned rod.

WILLIAM R. E. NOHSE.
